LIQUID-FUEL HEATING APPARATUS

Malcom W. Patrick, Macedonia, Ohio, assignor to Perfection Industries, Incorporated, a corporation of Ohio.

Application July 10, 1953, Serial No. 367,301

8 Claims. (Cl. 126—93)

This invention relates to heating apparatus of the class commonly referred to as space heaters, and it has to do with improvements in the design and construction of such apparatus, and with a unique form of liquid fuel burner especially adapted for use therein.

The general object of my invention is to provide an efficient natural draft liquid fuel burning space heater that is designed and constructed for use particularly in temporary or makeshift quarters where operating conditions are likely to be unfavorable, and that can be placed directly upon the ground, if necessary, and staked thereto, while the flue, that is incorporated in the apparatus, is held in a substantially vertical position by guy ropes or similar means.

It is a further purpose to provide a so-called "knock-down" construction, consisting of relatively few parts, including a housing of comparatively small compass, which parts are especially convenient of assembly and disassembly, and when disassembled are, with the exception of said housing, capable of being nested together and compactly arranged within the housing thereby to produce a package that is convenient of handling, transportation and storage.

Another object of the invention is to provide heating apparatus of the aforesaid class, that is simple of construction and inexpensive to manufacture and that will efficiently and satisfactorily burn liquid hydrocarbon fuels of various kinds, particularly those of a highly volatile nature such as gasoline, and that may be easily and safely lighted.

Another object is to provide a liquid fuel burner wherein in the point of admission of fuel to the burner casing is so remote from the combustion region that, even with highly volatile fuels, possibility of flash back from such region to the point of admission is reduced to a minimum.

Another object is to provide a natural draft liquid fuel burning apparatus wherein the burner, proper, is generally of the pot type in principle and is free of any internal obstruction that would interfere with or reduce the effectiveness of the natural draft.

Another object is to provide a burner of the character just described comprising a casing shaped throughout its lower region to form a sump for a pool of fuel and to maintain constant the exposed surface area of a pool of given volume regardless of any angle to which the burner may be tilted from vertical position within reasonable limits.

The invention readily lends itself to embodiment in heating apparatus of a wide range of sizes, throughout which range the apparatus is proportionately effective. As indicative of its effectiveness I may point out that in a structure wherein the heater housing is approximately 30 inches high and 7 inches in diameter, the heater is capable of a fuel burning rate that will produce a heat output in the neighborhood of 30,000 B. t. u.'s per hour.

Another object of the invention is to provide a liquid fuel burning apparatus that will operate over a wide range of fuel burning rates in a stable and quiet manner with-

out smoking, and that will not be affected by such disturbances as down drafts.

A still further object is to provide an especially simple means for effecting a continuous and uniform flow of fuel to the vaporizing region of the burner at any setting of the flow control valve, including those settings responsible for the lower rates of fuel feed, thereby to insure a steady fire and prevent fluctuation and possible extinguishment of the flame.

10 A yet further object is to provide a construction wherein the parts interfit in such manner as to be properly located with respect to one another and to be positively held in operative relation without the use of extrinsic fastening means, this feature being especially valuable in the knock-down construction hereinbefore referred to.

With these objects in view, and others that will become apparent as this description proceeds, the invention may be defined as consisting of the combination and arrangement of parts set out in the claims annexed hereto and illustrated in the accompanying drawings, wherein like reference characters designate like parts throughout the several views.

In the drawings,

Fig. 1 is a perspective view of my improved heating apparatus in condition for use, the view being divided into offset parts to permit of a larger scale;

Fig. 2 is a central vertical section through the apparatus in "knock-down" and compacted condition for transportation and storage;

Fig. 3 is a section on the line 3—3 of Fig. 2;

Fig. 4 is an enlarged central vertical section through the apparatus, with the flue and a part of the housing intermediate the ends of the combustion chamber broken away;

Fig. 5 is a horizontal section through the apparatus immediately above the bottom of the housing, as indicated by the line 5—5 of Fig. 4;

Fig. 6 is a vertical transverse section through the U-shaped burner casing, substantially on the line 6—6 of Fig. 4, showing the adjacent part of the housing and revealing the interengaged notched portions of the housing and burner, and

Figs. 7, 8 and 9 are perspective views, respectively, of the housing top, the housing bottom, and one of the hold-down lugs.

According to my present preferred construction, the housing 1 of the apparatus comprises an elongated cylindrical wall 2 of sheet metal of suitable gauge and quality. At a substantial distance above its lower end, the wall 2 is provided with an inwardly directed circumferential bead 3. Opening through the bottom edge of the cylindrical wall 2 is an arch shaped opening 4, and at the top of the opening, and coincident with the vertical axis thereof, is a notch 5.

Telescoped over and desirably permanently attached to the upper end of the wall 2 is a circular peripherally flanged top 8, within an elliptical opening of which is fitted a similarly shaped flue thimble 9. The thimble 9 has an outwardly extending flange 10 at its upper end that overlies the top 4 and is desirably welded thereto, and at its lower end the thimble is provided with an inwardly directed flange 11 that forms a seat for the flue that is designated, generally, by the reference numeral 12. The top 8 is shown as permanently fastened to the cylindrical wall 2 of the housing by a suitable number of depressions or so-called "dimples" 14, although any other expedient, such as welding, may be employed.

15 denotes an annular member, having a depending peripheral flange 16 that is of an outside diameter enough less than the inside diameter of the cylindrical wall 2 to permit of the member being inserted upwardly within said wall until it is positioned therein by engagement with the

bead 3. The member, when so positioned, defines the bottom of a combustion chamber C. The member 15 is provided with a relatively large central opening 18 that is surrounded by an upstanding cylindrical flange 19, in-turned at its upper end to form a seat 20.

25 denotes, generally, a liquid fuel burner that is made up in most part of a U-shaped casing 26. The casing is desirably constructed of sheet metal halves having flanges 27 and 28 along their inner and outer edges, respectively, that meet in the central vertical longitudinal plane of the casing. As indicated especially in Fig. 4, the flanges are welded together along their outer edges. Butt welded to the inner branch of the U-shaped casing is a cylindrical throat member 30 that is provided with air admitting openings 31, shown as arranged in circumferential rows. The outer branch of the U-shaped casing 26 encloses what, for the present, may be termed a fuel receiving space 33, while the inner branch encloses a carbureting space 34. Between these spaces and adjacent the bottom of the casing is a vaporizing region 35. The wall of the casing that encloses the carbureting space is provided with air admitting openings 36.

Detachably applied to the lower end of the cylindrical wall 2 of the housing 1 is a circular bottom 40, having a cylindrical flange 41 that telescopes over the lower end of said wall. Frictionally engaging the inner side of the wall in the plane of the flange 41, and at spaced intervals thereabout, are spring clips 43 whose in-turned lower ends 44 are welded to the bottom 40.

Slidably engaged through holes in the cylindrical wall of the housing adjacent the lower edge thereof are the parallel branches of a number (desirably three) of so-called hold-down lugs 45, each being constructed of a piece of rod of suitable diameter, and the inner ends of the branches of each lug are turned upwardly to form a stop to limit the outward movement of the lug, the lug being retractible until its central portion lies closely adjacent the flange 41 of the bottom 40. Said flange 41 is notched for the reception of the branches of the lugs when the bottom is applied to the housing. The upper edge portion of the flange 41 is cut away throughout the width of the arch shaped opening 4 of the wall 2, and said flange is provided intermediate the ends of the cutaway portion with a notch 48 that is in vertical alignment with the previously mentioned notch 5 of the wall 2. The flanges 27 and 28 of the burner casing 26 are also notched on the vertical axis of the burner casing, and when the inner branch of the burner casing is inserted through the opening 4 and the throat 30 is engaged within the flange 19 of the annular member 15, in contact with the seat 20 thereof, the notch of the flange 27 of the burner casing registers with the notch 5 of the wall 2 and, likewise, the notch of the flange 28 of said casing registers with the notch 48 of the bottom 40. Accordingly, when the bottom 40 is in normal relation to the wall 2, the burner is firmly held in the position described, the flanges of the burner casing interlocking with the cylindrical wall and bottom of the housing in the regions of the aforesaid notches, and in a manner obvious from the construction.

A closure 50 fits within the outer branch of the burner casing 26 and is permanently secured in place by welding the horizontal peripheral flange 51 of the closure to the end of said branch. The closure is shown as having a depressed peripheral portion and an elevated central portion within the latter of which is a lighting opening 52 that is normally closed by a disc-like cover 53. Said cover has spaced apertures through which the elongated shanks 54 of a wire retainer 55 extend, the lower ends of said shanks being turned outwardly for engagement with the underside of the adjacent portion of the closure 50 when the cover is lifted by means of a handle 56, formed as a ring from the central portion of the wire retainer 55. The cover is desirably provided with a peep hole 57 through which the operation of the burner may be observed.

Projecting through a hole in the closure 50 that is laterally spaced from the lighting opening 52 is the discharge end of a fuel supply conduit 60. Said discharge end, in the present instance, consists of an elbow 61, the inner end of which defines what may be referred to as the fuel feeding orifice 62.

65 denotes a so-called dripper wire, which term is intended to embrace any equivalent element that functions in substantially the same way as said wire. Its proximal end is extended upwardly through the orifice 62, substantially centrally of the vertical branch of the elbow 61, and the wire is shown as secured in place by having its upper end projected through a hole in the elbow and welded to the latter about said hole. In the region of the orifice, the wire is desirably offset laterally for contact with the outlet end of the elbow directly below the lateral branch of the latter. Thence the wire continues downwardly and toward the central portion of the burner casing where it terminates a suitable distance above the bottom thereof.

Included in the fuel supply conduit is the casing 68 of a conventional needlepoint valve 69, on the upstream side of which the casing has a lateral branch 70 that is adapted to be joined, by a coupling 71, to a pipe 72, 10 that leads from a suitable source of supply, such as a tank (not shown). It may be explained that the tank is located above the level of the burner so that the fuel will feed by gravity. The pipe 72 is desirably flexible and may consist of plastic tubing. The valve casing 30 68 is provided with a sight opening 73 through which the feeding of the fuel may be observed when the valve 69 is open.

If desired, a window 80 may be provided in the cylindrical wall 2 of the housing 1 through which the character 35 of the flame that is present in the combustion chamber C may be observed. The window, in the present case, is made by cutting a rectangular opening in said wall and attaching to the wall about said opening a frame 81 between which and the portion of the wall immediately 40 surrounding said opening is confined the marginal portion of a pane 82 of mica or the like.

The top 8 of the combustion chamber is provided with apertures 84 which act as "breather holes" to prevent the establishment of a resonant condition within 45 the combustion chamber and thereby assure quiet operation of the burner through its normal burning range.

The flue 12, hereinbefore referred to, desirably consists of a stove pipe made up of sections 85, 86 and 87 that are joined one to another in the usual way, but 50 differentiating from a conventional stove pipe in that the longitudinal seam of each section is separable. As will appear from Fig. 3, the lateral edges of the sheet metal blank from which each of the sections is made, are formed for interengagement in an obvious manner 55 for the purpose of retaining the section in tubular condition.

With the sections in such condition, they are joined together to form the flue 12, the lower end of which snugly fits within the thimble 9, in the top of the housing 1, 60 against the flange 11.

Over the upper end of the top section 87 is telescoped the lower end of a draft diverter 90 of conventional character, excepting that it includes means for attaching guys 91 (incidentally through the medium of the diverter) to the upper end of the flue. According to the 65 present construction, each guy 91 consists of a length of rope 92 and an insert of chain 93 adjacent the flue for the obvious purpose of protecting the rope from the heat of the flue. In the erection of the apparatus, the guys are drawn tight and fastened to suitable anchorages or stakes to hold the apparatus in an upright position.

With the apparatus assembled and set up, as illustrated in Figs. 1 and 4, it is placed in operation by first 70 opening the fuel control valve 69 and admitting a limited amount of fuel to the burner casing 26. As this fuel

is admitted, it runs down the dripper wire 65 and accumulates in a small pool in a sump provided by the bottom portion of the burner casing. The fuel in this pool is then ignited by a match or torch introduced through the lighting opening 52, after the cover 53 has been lifted from said opening by the handle 55 until stopped by engagement of the outwardly turned lower ends of the shanks 54 with the underside of the closure 50. A small flame ensues, and a mixture of the resultant products of combustion and unburned fuel vapors rises from the pool and is drawn toward the throat of the burner by the action of the draft induced by the chimney or stack 12. Air, which serves as primary air under present conditions, enters the burner casing through the openings 36 and commingles with the mixture of products and vapor. During the present or lighting phase, substantially all of the combustion occurs in the region of the air admitting openings 36.

It has been found advisable, during the first few moments following the lighting of the burner, to keep the cover 53 removed from the opening 52 as this allows air to enter the burner casing and sweep past the pool of fuel in the sump so as to assist in the vaporization of the fuel. After the burner parts have become heated, however, the heat radiated therefrom is sufficient to vaporize the amount of fuel necessary to sustain combustion, and said cover may now be replaced over the lighting opening.

As combustion continues, the burner casing becomes heated and the pool of fuel in the sump tends to vaporize more rapidly until finally, when equilibrium is reached, i. e., when the burner is operating efficiently and satisfactorily at or near maximum fire due to a balance of vapor and air at the present valve setting, the process of combustion is found to originate in the vicinity of the primary air openings 36 and to advance to full intensity in the region of the throat openings 31, attaining completion within the combustion chamber.

During high fire operation, the burner operates with a very small pool of fuel in the sump. It is desirable that a small pool be maintained when the burner is in operation at relatively high fire for this tends toward a stabilized fire condition.

It appears that small peephole 57 in the lighting cover 53 admits a limited amount of air, producing a current that carries the fuel vapors from above the pool of fuel to the combustion zone during normal operation. However, insufficient air is entrained through the peephole to support combustion in the region of the fuel discharge orifice 62. As a result, this region of the burner operates at such a relatively low temperature that no carbon or other objectionable residue is deposited about the fuel discharge orifice, and therefore the fuel supply rate remains constant.

It might be well to explain here that, due to the shape of the burner casing, the surface area of a pool of fuel of given volume that reposes within the sump constituted of the elbow portion of the casing is always the same, regardless of whether the apparatus is tilted perceptibly from an upright position. Accordingly, the size of the fire, at any setting of the control valve 69, is unaffected by a tilting of the apparatus within reasonable limits.

For the purpose of explanation, the interior of the burner casing may be considered as divided roughly into three zones: the first, including the region within the outer branch of the U-shaped casing 26 from the top thereof to about the center of the burner. The second zone extends from the first zone into the inner branch of the casing to about the lower end of the throat member, and the third zone continues thereabove through the throat member into the combustion chamber. During high fire operation (wherein the fuel consuming rate in an apparatus of the size hereinbefore mentioned is approximately 15 cc. per minute, with a heat output in the

neighborhood of 30,000 B. t. u.'s per hour), combustion is most intense in the third zone, with practically no combustion occurring in the second zone and, of course, none in the first zone. When the fuel supply is decreased to 5 the low fire rate (3 to 6 cc. per minute with an output of 7,500 to 15,000 B. t. u.'s per hour) combustion is initiated and practically completed in the second or intermediate zone. Under this present low fire condition, all the 10 necessary primary and secondary air enters through the openings 36 in the inner branch of the burner casing below the throat member. Even at this reduced fire there is no tendency for the flame to flash back to the fuel discharge orifice 62, and no combustion occurs in the region thereof or, in other words, in the first zone. This may 15 be accounted for by the fact that the burner parts in the immediate vicinity of the orifice are relatively cool, as before stated, and therefore have little tendency to generate and ignite vapor even though said parts be wetted by the fuel.

It is manifest from the foregoing that the burner, proper, operates at a lower temperature during high fire, when combustion occurs within and is confined to the third zone, i. e. the region of the throat member and the combustion chamber, than it does at low fire, when combustion is largely confined to the second zone, or in other words to the interior of the inner branch of the 20 burner casing.

After the apparatus has been placed in operation, the size of the fire is, of course, determined by the amount 30 of fuel fed, and this, in turn, is controlled by adjusting the valve 69 and observing the descent of the fuel through the valve casing 68 past the sight opening 73 therein. For minimum fire, in an apparatus of approximately the 35 size referred to, the valve 69 is adjusted to effect a feed of about two drops of fuel per second. Feed for maximum fire is attained when the valve has been opened sufficiently to cause the drops to merge into a continuous stream. At minimum fire, with combustion occurring 40 well down in the burner casing, the burner parts, including the lower portion (probably two-thirds) of the dripper wire, will be heated to a relatively high degree, the temperature of said portion of the wire exceeding the boiling point of the fuel. Under these conditions, the fuel will drain down the wire in a thin stream until it 45 reaches the highly heated lower portion thereof when it will flash into vapor and join the air entering through the lower holes of the burner casing, producing therewith the volume of combustible mixture responsible for low fire. It is apparent that, during this phase, the burner 50 will operate with a dry sump; and because of the presence of the fuel on the upper portion of the dripper wire, and the drift of air through the outer branch of the casing as previously explained, the parts adjacent the fuel feeding orifice 62 will remain relatively cool, wherefore 55 there will be no likelihood of combustion occurring in the immediate vicinity of said orifice.

During high fire operation, when the burner parts, including the dripper wire 65, are relatively cool as a result of their remoteness from the flame which is now well up 60 within the throat of the burner and in the combustion chamber, the fuel will flow in a continuous stream of liberal volume down the full length of the dripper wire, further contributing to the wire's coolness, and descend therefrom into the sump, with the result that a pool is 65 maintained, from the surface of which the fuel is vaporized by heat radiated downwardly from the flame and the burner parts surrounding it. The vapor thus generated mixes with the so-called primary air that enters through the holes of the burner casing below the throat, 70 producing a rich mixture that is rendered combustible by secondary air that enters through the openings 31 of the throat member 30.

While I have described only low and high fire operations, it will be obvious that, at any intermediate stage, 75 the respective characteristics of these two extreme condi-

tions proportionately change, the characteristics of one modifying those of the other, according to the setting of the control valve.

When the apparatus is to be transported or stored, it may be disassembled in an obvious manner, after releasing the guys 91 and removing the stakes from the hold-down lugs 45. All parts but the housing 1 may now be arranged in compact condition in the latter, as illustrated in Figs. 2 and 3. After removing the draft diverter 90 from the end of the flue section 87, said section and those designated 85 and 86 are opened along their sides by disengaging their hooked edges. The sections may now be expanded and inserted in the housing along one side thereof, and the draft diverter, guys, flexible pipe 72, and other loose parts may be placed in the housing alongside the flue sections. The burner 25 is then arranged in the lower portion of the housing with the throat member accommodated by the opening 14. The annular member 15 may next be placed within the open end of the housing, as illustrated in Fig. 2, and the bottom 40 applied, with the hold-down lugs 45 retracted. Compacted in this fashion, the apparatus may be conveniently handled, transported, and finally stored in a relatively small space.

Having thus described my invention, what I claim is:

1. A liquid fuel burner comprising a U-shaped casing in the form of a tubular elbow of constant radius and uniform circular cross section from end to end, the casing having relatively short upstanding branches that are spaced apart a distance less than their diameter, and fuel delivery means having a fuel discharge orifice that opens into the top portion of the first branch of said casing, said first branch being provided with means in the vicinity of said orifice for admitting air in limited quantity to the casing and being otherwise closed at its upper end, the lower central portion of the casing being characterized by a bottom that curves upwardly in all directions thereby providing a sump for a pool of fuel whose surface will remain unchanged in area notwithstanding perceptible tilting of the casing from an upright position, the second branch of the casing terminating at its upper end in a perforated throat and having therebelow means for admitting air to the casing.

2. A liquid fuel burner comprising the combination and arrangement of parts defined by claim 1, and a dripper wire having its upper end in fuel receiving relation to said orifice and its lower end in close proximity to and directly above the sump.

3. In a liquid fuel burner, a substantially U-shaped casing in the form of a tubular elbow of constant radius and uniform circular cross section from end to end, the casing including two upstanding branches that are spaced apart a distance less than their diameter, the first branch enclosing a fuel receiving space and the second branch enclosing a carbureting space, the casing providing, by reason of its elbow formation, a fuel sump extending below said spaces, means for delivering liquid fuel to the receiving space, the second branch having perforations located above the sump for admitting combustion air to the carbureting space, and a dripper wire extending from the liquid fuel delivering means at the point of fuel discharge thereof toward and in proximity to and directly above the fuel sump.

4. In heating apparatus of the class described, a vertical housing, a wall disposed horizontally therein and defining the top of a burner compartment, said wall being provided with a relatively large opening, a substantially U-shaped burner casing including relatively short upstanding branches, the first of said branches being substantially closed at its upper end, means for delivering liquid fuel to the upper portion of said first branch, a fuel conveying element leading therefrom to the central bottom portion of the burner casing, the second branch being open at its upper end and joined to said wall about the aforesaid opening, said second branch being provided with means for admitting air thereto.

5. Heating apparatus comprising a vertically disposed cylindrical housing having an opening in one side adjacent the bottom thereof, an annular member within and disposed across the housing above said opening and defining the top of a burner compartment, a U-shaped burner casing including relatively short upstanding branches, said casing being arranged with its central portion disposed within the side opening of the housing with the first branch thereof outside the housing and the second branch within the housing with its upper end joined to said annular member about the opening therein, the last mentioned branch having means for admitting air thereto, the first branch being substantially closed at its upper end, and means for delivering liquid fuel to the first branch in the region of its upper end.

6. In heating apparatus of the class described, the combination of an elongated vertically disposed housing having a relatively large notch in one side thereof that opens through its lower end, a member within and disposed across the housing above said notch, said member defining the top of a burner compartment and having a relatively large opening, a substantially U-shaped burner casing including relatively short upstanding branches, the burner casing being disposed within said notch of the housing with one branch joined to the aforesaid member about the opening of said member, said branch having means for admitting air thereto, the other branch being disposed outside the housing and being substantially closed at its upper end, means for delivering liquid fuel to the last mentioned branch adjacent the upper end thereof, and a bottom applied to the lower end of the housing, the burner casing having parts interengaging with parts of the housing and said bottom for maintaining the burner casing in fixed relation to the housing.

7. Heating apparatus comprising an elongated vertically disposed cylindrical housing, the housing being provided with a relatively large arch like notch that opens through the lower end of the housing, stop means on the interior of the housing above the top of said notch, an annular member having a relatively large opening and adapted to be inserted upwardly into the lower end of the housing and engaged with said stop means thereby to define the top of a burner compartment, a bottom detachably applied to the lower end of the housing, a U-shaped burner casing including relatively short upstanding branches, said casing being arranged with its central portion within the aforesaid notch of the housing with its inner branch joined to said annular member about the opening thereof, said inner branch having means for admitting air thereto, means substantially closing the upper end of the outer branch of the burner casing, and means for delivering liquid fuel to said outer branch adjacent the upper end thereof, the burner casing having means interengaged with the housing and bottom in such manner as to be retained in operative position with respect thereto.

8. A knock-down heating apparatus comprising an elongated vertically disposed housing, the housing being provided with a relatively large arch-like notch that opens through the lower end of the housing, stop means on the interior of the housing above the top of said notch, an annular member having a relatively large opening and adapted to be inserted upwardly into the lower end of the housing and engaged with said stop means, a top for the housing, the housing being provided with a flue connection, a collapsible flue separately connected thereto, a bottom detachably applied to the lower end of the housing, a U-shaped burner casing including relatively short upstanding branches, said casing being adapted to be arranged with its central portion within the aforesaid notch of the housing and with its inner branch engaged with the annular member about the opening thereof, the burner casing having means adapted to be interengaged with the housing and bot-

tom in such manner as to be removably retained in operative position thereby and serving, when in such position, to maintain the annular member adjacent the aforesaid stop means, the foregoing elements being so related in size that when disassembled all but the housing are capable of being arranged in compact form within the housing with the bottom applied to the latter.
